CHARLES H. MORTON
INVENTOR.
BY George T. Folke,
ATTORNEY.

UNITED STATES PATENT OFFICE.

CHARLES HENRY MORTON, OF ECCLES, ENGLAND.

CHAIR.

1,360,776.

Specification of Letters Patent. Patented Nov. 30, 1920.

Application filed May 20, 1920. Serial No. 383,009.

To all whom it may concern:

Be it known that I, CHARLES HENRY MORTON, a subject of the King of Great Britain, residing at Hillside, Gilda Brook Road, 5 Eccles, Manchester, England, has invented a new and useful Improvement in Chairs; and he does hereby declare the following to be a full, clear, and exact description of the same.

10 This invention has reference to a camp or deck chair which may be constructed of wood, metal, or other suitable substance and is so constructed that it can be used in either an upright or lounge position, said 15 chair also being adapted to be collapsed in the ordinary manner.

The present invention comprises a chair adapted to be alternatively employed in an upright position with a horizontal seat or 20 a lounge position with a flexible seat by means of a different or alternative positioning of the chair supports (or legs), the said chair being also adapted to be folded or collapsed for the purpose of storage or the 25 like when not in use.

The invention will now be described with particular reference to the accompanying sheet of drawings, in which:—

Figure 1 is a side elevation of the chair 30 in the upright position.

Fig. 2 is a side elevation of the chair in the lounge position, and

Fig. 3 is a plan of the chair in the collapsed position.

35 Referring first more particularly to Fig. 1, the back of the chair A is free to move forward about its fulcrum C but is prevented from moving backward beyond the position seen in Fig. 1 of the drawings by 40 the lower extremity A¹ of the back A engaging with the end of the seat D. The seat D is adapted to engage by means of the slot E with a cross rail F secured to the legs G, the legs G being pivoted by means 45 of the bolts or rivets H to the rectangular leg and back member J. The rail K at the upper end of the member J has secured thereto a length of canvas L which is also connected to the rail M attached to the legs 50 G. The member J is pivotally connected to the seat D by means of the rivet or the bolt N, and the seat is provided with cross rails as O, and the back A is provided with cross rails as P.

55 When the chair is turned to the position

seen in Fig. 2 it forms a deck or lounge chair of familiar character and it will now be observed that the opposite end of the legs G are in contact with the supporting surface for the chair to those which support the chair when in the upright position seen in Fig. 1. No adjustment of the parts of the chair is necessary to effect this change from the one form of chair to the other as the parts automatically move to the illustrated 60 position by a mere turning operation of the chair from the one position to the other.

When it is desired to collapse the chair for purposes of storage or the like the members can be folded or collapsed to the position seen in Fig. 3 when the length and depth occupied by the chair is substantially equivalent to that of the length and thickness of the rectangular frame.

Claims:—

1. A chair adapted to be alternatively employed as a horizontally seated chair or as a lounge chair, the chair frame and members being so constructed and arranged that when used as first stated, a rigid member 80 forms the horizontal seat and when used in the lounge position a flexible member forms the seat and back, by an alternative positioning of the chair supports.

2. A chair adapted to be alternatively employed as a horizontally seated chair or as a lounge chair, the chair frame and members being so constructed and arranged that when used as first stated, a rigid member forms the horizontal seat and when used in 85 the lounge position a flexible member forms the seat and back, by an alternative positioning of the chair supports, said chair being adapted to be folded or collapsed.

3. A chair adapted to be alternatively employed in an upright position with a rigid horizontal seat and vertical back, or in a lounge position with a flexible seat and back, by means of an alternative positioning of the chair supports, said chair embodying two alternative back frames for use with the alternative positioning of the chair, said frames being pivotally connected to each other.

4. A chair comprising a rectangular frame, a rigid seat and legs pivoted to said frame, and a flexible seat connected to said frame and legs, said chair being adapted for an alternative positioning which permits of an alternative use of the two seats.

5. A chair comprising a rectangular frame pivotally connected to a rigid back frame, to a rigid seat, and to legs which are adapted for connection to said seat, said rectangular frame and legs being connected by a length of canvas or the like flexible material.

6. A chair having in combination a main supporting frame and a subordinate supporting frame pivotally connected to said main frame, a flexible seat suspended between the frames, and a rigid member pivoted to said main frame which forms a seat when the chair is set in the upright position.

tion, and forms a strut when the chair is set 15 in the lounge position.

7. A chair having in combination a main supporting frame and a subordinate supporting frame, pivotally connected to said main frame, a flexible member connecting 20 said frames and forming a seat and back when the chair is set in the lounge position, and a rigid member pivoted to the main frame which forms a horizontal seat when the chair is set in the upright position. 25

In testimony whereof, I have signed my name to this specification.

CHARLES HENRY MORTON.
